UNITED STATES PATENT OFFICE.

JOHN KARPEN AND CHARLES A. BARROW, OF RACINE, WISCONSIN.

DESIGN FOR A BOTTLE-STOPPER.

49,123.

Specification for Design.

Patented May 30, 1916.

Application filed March 6, 1916. Serial No. 82,507. Term of patent 7 years.

To all whom it may concern:

Be it known that we, JOHN KARPEN and CHARLES A. BARROW, both citizens of the United States, residing at Racine, in the county of Racine and State of Wisconsin, have invented a new, original, and ornamental Design for Bottle-Stoppers, of which the following is a specification, reference being had to the accompanying drawing, forming part thereof.

In the drawings Figure 1 is a side elevation of a bottle stopper, showing our new

design; and Fig. 2 is a plan view of the same.

We claim:

The ornamental design for a bottle stopper, as shown.

In testimony that we claim the foregoing we have hereunto set our hands at Racine, in the county of Racine and State of Wisconsin.

JOHN KARPEN.
CHARLES A. BARROW.
